[57] CLAIM

I claim a combination whiteboard, as shown and described.

DESCRIPTION

FIG. 1 is a perspective view of a combination whiteboard showing my new design, the two writing instruments depicted by means of broken lines being shown for illustrated purposes only and forming no part of the claimed design;

FIG. 2 is a front elevational view;

FIG. 3 is a bottom plan view; and

FIG. 4 is a right side elevational view, the left side being a mirror image thereof.

The rear of the article is unornamented.

1 Claim, 2 Drawing Sheets
